UNITED STATES PATENT OFFICE.

FRANK T. JONES, OF BALTIMORE, MARYLAND, ASSIGNOR, BY MESNE ASSIGNMENTS.
TO THE AMERICAN TRAIN CONTROL COMPANY, A CORPORATION OF MARYLAND.

SPEED-CONTROLLING MECHANISM FOR VEHICLES.

1,131,637.

Specification of Letters Patent. Patented Mar. 9, 1915.

Application filed June 18, 1913. Serial No. 774,287.

To all whom it may concern:

Be it known that I, FRANK T. JONES, a citizen of the United States, residing at Baltimore, in the State of Maryland, have invented certain new and useful Improvements in Speed-Controlling Mechanism for Vehicles, of which the following is a specification.

This invention relates to an automatic speed controlling mechanism for railway vehicles and has for one object to provide an improved means for requiring the speed of a train or vehicle to be reduced under certain road conditions, or be brought to a stop. And another object is to provide an improved means whereby a train or vehicle may proceed at a greatly-reduced or safe speed when the track ahead is occupied by another train or is otherwise in a condition where a high speed would be dangerous.

The invention herein set forth relates more particularly to a novel arrangement of track mechanism which is operated in connection with a train control system wherein a normal circuit and current on the engine or other vehicle is interrupted during the passage of contact shoe, which the engine or vehicle carries, over ramp rails which are located at intervals along the trackway, and during which interruption, if the vehicle is to proceed, a substitute current will be picked up from the ramp rail by the shoe and supplied on the engine or vehicle while the said normal vehicle current and circuit is broken thereby enabling the substitute current to do the work of the normal vehicle current either in holding the brakes off or allowing the steam or other motive power conditions to remain such on the vehicle as to permit the latter to proceed.

An example of an apparatus on the vehicle such as above noted will be found in U. S. Patents, 1,010,371 and 1,010,372 to which attention is directed.

The present invention therefore relates to a safety train control mechanism whereby a train may enter a block already occupied or in which the track conditions are altered and not in condition for high speed, provided such train enters the block at a much reduced speed or a speed that will enable the engineer to maintain sufficient control to stop upon reaching the place of danger. On the other hand if the engineer disre-

gards the signals or the lack of a signal to proceed and attempts to enter, at a high speed, a block already occupied or in which the track conditions demand caution, the train will be automatically stopped.

With these objects in view the accompanying drawings illustrate in a diagrammatic way, embodiments of the inventive idea, in which drawings,

Figure 1, shows a diagrammatic arrangement of the vehicle and track circuits the latter being occupied by a train and in condition to stop the rear vehicle if the latter should approach the block above a low or safe speed, but allow the vehicle to proceed at a safe speed. Fig. 2, illustrates the invention in a diagrammatic way as applied to a stretch of track where a switch is located, and Fig. 3, shows a side view of one of the ramp rails.

In carrying out the invention I utilize the track rails, 1, as a part of a track circuit and interpose insulation, 2, in the rails at intervals to form blocks or sections. Each block or section is provided with a current supply, 3, one side of which supply is connected by a conductor, 4, to one rail and the other side of the supply being connected by a conductor, 5, to the other rail. In the present instance two blocks or sections, 6, and, 7, respectively are shown and the safety control device on the trackway for block, 7, only is shown. Each block or section, in the present instance has a caution ramp rail, 8, and a stop ramp rail, 9—both of which are located at a convenient place with respect to the track rails—the caution ramp rail in the present instance being shown slightly farther from the track than the stop ramp rail in order that the two ramp rails shall be out of alignment to permit one shoe on the vehicle to engage one ramp rail and another shoe also on the vehicle to engage the other ramp rail, as will presently be more fully explained. The two ramp rails, 8, and, 9, have connection by wires, 10, and, 11, and, 12, with a switch, 13, which latter has two contact arms, 14, and, 15, respectively and the switch, 13, is controlled by an electro-magnet, 16, which latter is connected by wires, 17, and, 18, to the two track rails of the section or block, 7.

By referring to Fig. 1 of the drawing it will be seen that the caution and stop ramp

rails, 8, and, 9, for block, 7, are located adjacent to the exit end of block, 6, but that the electro-magnet, 16, which controls the switch, 13, with which those ramp rails, 8, 5 and, 9, are connected, is normally actuated by a track current from the battery, 3, and rails, 1, of block, 7. By this arrangement of the track circuit through the electro-magnet, 16, when the block, 7, is clear and unoccupied by a vehicle, the said magnet will normally be energized so as to hold the switch, 13, attracted and in one of its two positions and when so held the arm, 15, of the switch will engage a contact, 19, from which 10 a wire, 20, leads to and connects with one side of a local battery or current supply, 21. It will thus be understood that when block, 7, is clear, electro-magnet, 16, will be energized by the track current from said block, 15 and that the electro-magnet will attract 16 switch, 13, so that arm, 15, of the latter will engage contact, 19, and have a connection through wire, 20, with one side of the local current supply or battery, 21. It will also 20 be seen that when arm, 15, engages contact, 19, that both ramp rails, 8, and, 9, will have a connection with the said one side of local current supply or battery, 21, through wires, 10, 11, and, 12, and switch, 13. Therefore 25 when block, 7, is clear, both ramp rails, 8, and, 9, will have a connection with the one side of the local battery or current supply, 21. When however block, 7, is occupied by 30 a vehicle, 22, as shown in Fig. 1, the track current from that block will be cut off from electro-magnet, 16, and the switch arm, 15, will drop away from contact, 19, and break 35 the connection from the one side of local current supply or battery, 21, to both ramp 40 rails.

A conductor, 23, has one end connected with one of the track rails and the other end of said conductor leads to and is connected with the other side of the local current supply or battery, 21. It will thus be understood that when the block is clear one side of the local current supply or battery, 21, of the controlling device for that block, 45 will be connected to one of the track rails of the block next preceding it while the other side of said local current supply or battery, 21, will have connection with both the caution and the stop ramp rails, 8, and, 50 9, but when the block is occupied the connection from the local current supply to the ramp rails, 8, and, 9, will be broken because switch arm, 15, will have dropped away 55 from contact, 19, as shown in Fig. 1, of the drawing.

60 In so far as has been described the device is substantially the same as set forth in the Patents 1,010,371 and 1,010,372 heretofore referred to in so far as the ramp rails are connected or disconnected with a local current supply when a block ahead is clear or

occupied but in addition to this the present invention proposes to allow the train to proceed at a safe speed although the block ahead is occupied or in case the track conditions of said block ahead are such that high speed would be dangerous. To do this special circuits must be provided on both the vehicle and the trackway which coact to prevent a stoppage of the vehicle if the latter is proceeding slowly but to bring the train to a stop if the speed is above a predetermined low speed. Each controlling device guarding the entrance to a block is provided with a local electro-magnet, 24, whose action indirectly causes a train or vehicle to be stopped, or allow such vehicle to proceed, depending on the condition of the track ahead and the speed at which the vehicle is traveling. This local electro-magnet, 24, is so arranged that during occupancy 85 by a vehicle of the block which it is guarding, it (said magnet) will be interposed between the ramp rails and the track rail but said magnet will not be energized because of no current supply during the absence of a 90 second vehicle or train. The said interposition of this electro-magnet, 24, is effected from the ramp rail, 9, by conductors, 12, and, 11, to switch, 13; switch-arm, 14, to a contact, 25, and by conductor, 26, to electro-magnet, 24, then through resistance, 27, to conductor, 23, and by the latter to track rail, 1. It will thus be noted that while electro-magnet, 24, has one connection with ramp rail, 9, and another connection with 100 track rail, 1, said connections are only maintained through the switch, 13, and then only when conditions in block, 7, are such that a train or vehicle should not enter from block, 6, except at a slow speed, because at 105 such times the position of the switch is such that its arms, 14, will engage contact, 25.

An armature, 28, is so located with respect to electro-magnet, 24, that it may be attracted upon the energization of said magnet and when so attracted said armature will move into engagement with a contact, 29. This contact, 29, has connection through a conductor, 30, to one side of local current supply or battery, 21, and when the armature, 28, has been moved by electro-magnet, 24, into engagement with contact, 29, the connection from the said one side of local current-supply or battery, 21, will be extended through the armature, 28, and by wire, 31, 115 to electro-magnet, 24, and conductor, 26, to switch, 13, and then by conductors, 11, and, 12, to ramp rail, 9. It will therefore be seen that when electro-magnet, 24, is energized 120 it will move armature, 28, to engagement with contact, 29, whereupon a connection will be made from one side of the local current supply or battery, 21, through magnet, 24, to keep the latter energized and then 125 to the stop ramp rail, 9. At such time there 130

will also be a connection from the other side of the local current supply, 21, by conductor, 23, to track rail, 1, in block, 6.

The armature, 28, is connected with a retarding device to cause it to move slowly when electro-magnet, 24, is first energized so as to effect a delay or a time interval between the time the electro-magnet, 24, is energized and the moment when armature, 28, will reach contact, 29. The particular form of this retarding device is immaterial so long as it will effect a delay in the engagement of armature, 28, with contact, 29. The exact delay is also not essential and may be one time-period or another, but, it is desirable that the delay be uniform because the energization of the electro-magnet, 24, takes place as the result of conditions in the block ahead which make it desirable that a train or vehicle should proceed at a safe speed and such energization actually occurs only when the vehicle reaches the ramp rail, 9, and the speed of the vehicle is to be taken into account. The retarding device however, in the present instance comprises a plate, 32, whose lower end projects into a receptacle, 33, containing oil so that when armature, 28, moves, a movement will be imparted to the plate, 32, which must displace the oil in making its movement, thereby retarding its operation.

The vehicle mechanism and circuits are illustrated diagrammatically in Fig. 1, and will now be briefly described. One wheel, 34, of the vehicle is shown and a magnetic controlling device, 35, for either steam or air is shown as carried on the vehicle. A caution contact shoe, 36, and a stop contact shoe, 37, are also illustrated as part of the vehicle equipment as is also a signal such as a bell, 38. A switch, 39, is also provided on the vehicle in such relation to the stop contact shoe, 37, that a rod, 40, may be actuated by the shoe when the latter rides up onto a ramp rail, 9, and said rod will engage and cause the switch to be moved with respect to a contact, 41. A current supply or battery, 42, is also located on the vehicle and a conductor, 43, connects one side of the said current supply with the switch, 39, on the vehicle. From the switch contact, 41, a conductor, 44, leads to the valve or other controlling device, 35, and another conductor, 45, connects the said controlling device, 35, with the other side of battery, 42. It will thus be seen that the vehicle has a normal circuit from current supply, 42, through switch, 39, and valve or controller, 35, back to the supply which will by energizing an electro-magnet in said controller, 35, hold the controller in a position to allow the usual operations of the steam or air brake mechanisms. A conductor, 46, extends from the axle, 47, of the wheel to and connects with the conductor, 45, at one side of the

controlling device. Another conductor, 48, connects conductor, 46, with the signal or bell, 38, and one other conductor, 49, connects the bell or signal, 38, with the caution shoe, 36. It will also be noted by reference to the diagrammatic vehicle circuits that a conductor, 50, connects the stop shoe, 37, with the contact, 41, with which the switch, 39, engages. The stop shoe, 37, is presumed to be pivoted at, 51, to a bracket, 52, so that the end which carries the rod, 40, may move upwardly when the shoe passes onto the inclined end, 53, of the stop ramp rail, 9, which latter is shown in Fig. 3. The stop ramp rail, 9, may have a long gradually inclined end, 53, and then a second incline, 54, for a purpose presently to be explained. This however is not essential.

The operation of the devices above described will now be explained. It is believed to be clear that when the block is clear the energization of electro-magnet, 16, by the track current from battery, 3, will cause switch, 13, to be so moved and held by said magnet as to connect both ramp rails, 8, and, 9, with one side of local current supply, 21. During such clear track conditions the connections between the ramp rails, 8, 9, and the one side of local current supply, 21, will be as follows: By wires, 10, 12, and, 11, to switch, 13, and by switch arm, 15, contact, 19, and wire, 20. Thus it will be seen that one side only of the current supply, 21, will have a connection with both ramp rails. From the other side of the local current supply a conductor, 23, leads to and terminates at one track rail but there will be no complete circuit from said supply, 21, during the absence of a vehicle shoe from either ramp rail, 8, or, 9.

When the vehicle is traveling between ramp rails the controlling device, 35, on the vehicle will be held in running position by means of a vehicle circuit from vehicle current supply, 42, the circuit being from the supply, 42, by conductor, 43, through switch, 39, to conductor, 44, to magnetic controller, 35, then by conductor, 45, back to supply, 42. When the vehicle reaches the ramp rail, 8, the caution shoe, 36, will contact with the rail, 8, and immediately the circuit from local current supply, 21, will be completed from rail, 8, to shoe, 36, to conductor, 49, to signal, 38; then back by conductors, 48, 46, axle, 47, and wheel, 34, to track rail and then by wire, 23, back to battery, 21, thereby completing the circuit by picking up a current and giving a signal of safety on the vehicle. In a like manner when stop shoe, 37, reaches stop ramp rail, 9, said shoe will raise and move switch, 39, thus causing the normal vehicle circuit to be interrupted, but while doing this, the stop shoe will pick up the current from local supply, 21, (because switch, 13, will be moved so as to bring

arm, 15, and contact, 19, together) and convey the picked up current through conductor, 50, to, 44, to magnetic controller, 35, then return by conductors, 45, and, 46, to axle, 47, 5 and wheel, 34, to track rail and finally return by conductor, 23, to local current supply, 21, thereby completing a picked up current supply while the shoe is traveling over the stop ramp rail, 9, and the track ahead is clear. When however, a block is occupied, 10 or the track conditions in the block are such as to reduce the speed thereon, it is deemed proper by some that a vehicle should be permitted to enter that block in order to 15 maintain schedules, but at a much reduced speed, keeping the vehicle under control to be stopped quickly. The present invention therefore provides for this and the diagrammatic illustration in Fig. 1, shows the circuits in condition to allow the vehicle to 20 enter block, 7, at a reduced speed, although that block, 7, is occupied by the vehicle, 22.

By referring to Fig. 1 it will be noted that vehicle 22, has position in the block, 7, between the track current supply, 3, and the electro-magnet, 16, therefore said vehicle, 22, will cause a short circuit in the track current by the wheels and axles between the track rails. This causes the electro-magnet, 30 16, to become deenergized and the deenergization of said electro-magnet releases switch, 13, and allows switch arm, 15, to drop from contact, 19, thus breaking the connection between the switch arm and the 35 one side of local current supply, 21, and thereby breaking the connection from said local current supply to the two ramp rails, 8, and, 9. When switch arm, 15, drops however from contact, 19, the other arm, 14, of 40 that switch engages contact, 25, and at once a connection (but not a circuit) is formed through conductor, 26, to electro-magnet, 24, resistance, 27, and conductor, 23, to one of the track rails of block, 6. This is merely 45 a connection however, and no current passes through electro-magnet, 24, consequently that magnet is not energized.

When the second or following vehicle approaches block, 7, the signal shoe, 36, first 50 passes over ramp rail, 8, but owing to the break between switch arm, 15, and contact, 19, current from local supply, 21, cannot pass to the ramp rail, 8, and consequently the signal shoe cannot pick up a current to 55 operate the signal, 38, on the vehicle. The result is the lack of a signal to proceed and the engineer should immediately slow down. If the speed is cut down the vehicle will proceed slowly and the stop shoe, 37, will next 60 engage the stop ramp rail, 9, which latter is also cut off from the local current supply, 21, because of the break between contact, 19, and switch arm, 15.

When the stop shoe passes onto the low 65 end, 53, of stop ramp rail, 9, the shoe will

slowly move vertically but immediately upon making contact with the ramp rail, 9, the current from the vehicle supply, 42, will divide—same maintaining the normal vehicle circuit by conductor, 43, through vehicle switch, 39; conductor, 44, to and through the electro-magnet, 35, of the vehicle controlling device then back by conductor, 45, to the said supply, 42, thus keeping the controlling device from operating 70 to stop the vehicle, and part of the current from vehicle supply, 42, will pass through conductor, 50, to the shoe, 37, then through ramp rail, 9, and by conductors, 12, and, 11, to switch, 13, and switch arm, 14; then by 75 contact, 25, and conductor, 26, to and through electro-magnet, 24, energizing the latter, then through resistance, 27, and conductor, 23, to track rail, 1, and finally by wheel, 34, axle, 47, and conductors, 46, and, 80 45, back to vehicle current supply, 42. It will thus be seen that when the block, 7, is occupied and a second vehicle attempts to enter the same, the moment the stop shoe reaches ramp rail, 9, a current is picked up 85 by the ramp rail from the vehicle and sent through the electro-magnet, 24, to energize the latter and then returned to the vehicle and this occurs while the shoe, 37, and rod, 40, are both moving upwardly and before 90 the rod contacts with vehicle switch, 39, to break the normal connection between the switch and conductors, 44, and, 50. This picked-up vehicle current, as above stated 95 energizes electro-magnet, 24, and the energization of that magnet starts the armature, 28, toward the magnet, and toward the contact, 29, but the movement of this armature, 28, is retarded because of the plate, 32, sweeping through the oil in the receptacle, 100 33. This causes a predetermined period of delay in forming the connection between armature, 28, and contact, 29, and it is this period of delay that determines whether the vehicle shall be stopped or allowed to proceed. If the speed has been reduced and is safe the movement of the shoe, 37, over the ramp rail, 9, will be comparatively slow and before the rod, 40, on the vehicle has reached 105 the switch, 39, to move the latter the armature, 28, will have moved into engagement with contact, 29, which immediately throws local current supply, 21, again into connection with the ramp rail, 9, and allows current from said local current supply to be picked 110 up from the said ramp rail and sent through the controller magnet, 35, on the vehicle before the break in the local vehicle supply at switch, 39, takes place—the break at said switch, 39, taking place immediately after 115 the substitute current has been picked up by the shoe, 37, and sent through the vehicle magnet, 35. This picked-up circuit on reduced speed is as follows: from one side 120 of local current supply, 21, by conductor, 30, 125 130

contact, 29, armature, 28, conductor, 31, to electro-magnet, 24, keeping the latter energized; then by conductor, 26, contact, 25, switch arm, 14, switch, 13, and conductors, 11, and, 12, to stop ramp rail, 9; then through stop shoe, 37, conductors, 50, and, 44, to vehicle magnet, 35, keeping the latter energized; then return by conductors, 45, and, 46, to axle, 47, wheel, 34, to rail 1, and 10 finally by conductor, 23, back to current supply, 21.

If the speed of the vehicle is not reduced to at least a predetermined lower speed upon the failure to get a clear signal at ramp rail, 8, then the stop shoe, 37, will ride over the ramp rail, 9, too fast and not give the vehicle current time to be picked up by the ramp rail, 9, sent through the magnet, 24, and move the retarded armature, 28, against 15 contact, 29, before rod, 40, of the stop shoe moves the switch, 39, and the result is that if switch, 39, is moved before armature, 28, and contact, 29, are brought together, the vehicle magnet, 35, will become deenergized 20 and the controlling device will operate to 25 stop the vehicle.

From the foregoing it will be seen that when the block ahead is clear the local current supply, 21, will supply a substitute 30 current direct to the vehicle magnet while the normal vehicle circuit is broken by the stop shoe raising suddenly by passing quickly onto the stop ramp rail. When however the block ahead is occupied and 35 the vehicle maintains a high speed the local current supply will be cut off from the ramp rail and a stop will follow. On the other hand when the block ahead is occupied and the speed of the vehicle is reduced, the 40 vehicle current is first picked up by the stop ramp rail to actuate a timing device and if the speed is slowed down sufficiently, the timing device will form an indirect circuit from the local current supply to the 45 ramp rail which local current will then be picked up by the vehicle shoe and substituted for the normal vehicle circuit which latter then becomes interrupted. By utilizing the same principle of first picking up 50 the vehicle current to operate a local timing mechanism and then form an indirect circuit from the local current supply to the controlling device on the vehicle before the normal vehicle circuit is broken, the invention 55 is equally applicable for requiring a reduction of speed when a switch or crossover is being approached, as illustrated diagrammatically in Fig. 2 of the drawing. In this instance the same vehicle equipment 60 and track circuits are employed with the exception that the local circuit switch, 55, which is interposed between the local current supply, 21, and ramp rails, 8, and, 9, is operated by a mechanical connection, 56, 65 from the switch, 57. In this instance the

same contact points, 19, and, 25, are employed and the switch moves from one point to the other according to the position of the switch. If the switch connects with point, 19, the local current supply, 21, has one side 70 directly connected through the switch to conductors, 11, 12, and, 10, and then to the ramp rails, 8, and, 9, and if the switch is in engagement with contact, 25, that same local current supply can only be connected to 75 said ramp rails through conductor, 30, armature, 28, conductor, 31, timing electro-magnet, 24, and conductor, 26, to switch, 55, and conductor, 11, 12, and, 10, to the ramp rails. In this instance the mechanical connection, 56, takes the place of the electro-magnet, 16, in the form shown in Fig. 1 80 and the track switch, 57, is the dangerous object instead of the train, 22.

In all respects the operation is the same 85 as that explained in connection with the illustration in Fig. 1 and it is deemed unnecessary to detail it. In this instance if the switch is closed the vehicle can proceed at high speed and a clear signal will be given 90 at ramp rail, 8. When the vehicle reaches ramp rail, 9, if switch, 57, is closed the local current supply, 21, will be picked up by the stop shoe, 37. If the switch, 57, is open however, as shown in Fig. 2, no signal will be 95 given at ramp rail, 8, and a reduction in speed must be made or a stop will follow at ramp rail, 9. If speed is reduced the vehicle current will be picked up by ramp rail, 9, sent through the electrotiming magnet, 100 24, to operate armature, 28, and said armature will then close the indirect circuit from local current supply to ramp rail, 9, so the latter current can then be picked up and sent through vehicle magnet, 35, as a substitute for the normal vehicle current which 105 then becomes interrupted.

Having thus described my invention what I claim and desire to secure by Letters Patent is:

1. A safety controlling device for rail-ways wherein the vehicle is provided with a controlling device, an actuating device, and a normal vehicle circuit controlled by the actuating device and including the controlling device, in combination with the track rails formed into blocks; a contact means for each block with which the actuating means on the vehicle coacts to effect an interruption of the normal vehicle 115 circuit; a current supply and a normal connection from one side thereof to the contact means to supply a substitute current on the vehicle at times while the normal vehicle circuit is interrupted; means for interrupting the connection between the latter current supply and contact means when conditions in the block require low speed and means for reestablishing a connection from the said latter current supply through the 120 125 130

controlling device on the vehicle when the vehicle is traveling at a low speed.

2. A safety controlling device for railways wherein the vehicle is provided with a controlling device, an actuating device, and a normal vehicle circuit controlled by the actuating device and including the controlling device, in combination with the track rails formed into blocks; a contact means for each block with which the actuating means on the vehicle coacts to effect an interruption of the normal vehicle circuit; a current supply and a normal connection from one side thereof to the contact means to supply a substitute current on the vehicle at times while the normal vehicle circuit is interrupted; means for interrupting the connection between the latter current supply and contact means when conditions in the block require low speed and means actuated by the vehicle current for forming a connection from the said latter current supply through the controlling device on the vehicle when the latter is traveling at a low speed.

3. A safety controlling device for railways wherein the vehicle is provided with a controlling device, an actuating device and a normal vehicle circuit controlled by the actuating device and including the controlling device, in combination with the track rails formed into blocks; a contact means for each block with which the actuating means on the vehicle coacts to effect an interruption of the normal vehicle circuit; a current supply and a normal connection from one side thereof to the contact means to supply a substitute current on the vehicle at times while the normal vehicle circuit is interrupted; means for interrupting the connection between the latter current supply and contact means when conditions in the block require low speed and timing means actuated by the vehicle current for forming a connection from the said latter current supply to the said contact means when the vehicle is moving at a low speed.

4. A safety controlling device for railways wherein the vehicle is provided with a controlling device, an actuating device, and a normal vehicle circuit controlled by the actuating device and including the controlling device, in combination with the track rails formed into blocks; a contact means for each block with which the actuating means on the vehicle coacts to effect an interruption of the normal vehicle circuit; a current supply and a normal connection from one side thereof to the contact means to supply a substitute current on the vehicle at times while the normal vehicle circuit is interrupted; means for interrupting the connection between the latter current supply and contact means when conditions in the block require low speed and means interposed be-

tween the latter current supply and the said contact means and actuated by the vehicle current for forming a connection between said current supply and said contact means when the vehicle is traveling at a low speed. 70

5. A safety controlling device for railways wherein the vehicle is provided with a controlling device, an actuating device and a normal vehicle circuit controlled by the actuating device and including the said controlling device, in combination with the track rails formed into blocks; a contact means for each block with which the actuating means on the vehicle coacts to effect an interruption of the normal vehicle circuit; a local current supply having a normal connection from one side thereof to the said contact means; means for interrupting the said normal connection between the local supply and said contact means when conditions in the block require low speed, and means for forming a substitute circuit from the said local current supply through the controlling device on the vehicle when the latter is traveling at the required low speed. 85 90

6. A safety controlling device for railways wherein the vehicle is provided with a controlling device, an actuating device and a normal vehicle circuit controlled by the actuating device and including the said controlling device, in combination with the track rails formed into blocks; a contact means for each block with which the actuating means on the vehicle coacts to effect an interruption of the normal vehicle circuit; a local current supply having a normal connection from one side thereof to the said contact means; means for interrupting the said normal connection between the local supply and said contact means when conditions in the block require low speed; means interposed between the said contact means and the track rail while the connection between the local current supply and said contact means are interrupted whereby said interposed means may be actuated by the vehicle current, and means actuated by said interposed means for forming a circuit from said local current supply through the controlling device on the vehicle when the latter is traveling at the required low speed. 105 110

7. A safety controlling device for railways wherein the vehicle is provided with a controlling device, an actuating device and a normal vehicle circuit controlled by the actuating device and including the said controlling device, in combination with the track rails formed into blocks; a contact means for each block with which the actuating means on the vehicle coacts to effect an interruption of the normal vehicle circuit; a local current supply having a normal direct connection from one side to the said contact means; means for interrupting said direct connection when low speed of 120 125 130

the vehicle is required and means for forming an indirect connection from one side of the said local current supply through the said contact means to the controlling device on the vehicle when the latter is traveling at the required low speed.

8. A safety controlling device for railways wherein the vehicle is provided with a controlling device, an actuating device and a normal vehicle circuit controlled by the actuating device and including the said controlling device, in combination with the track rails formed into blocks; a contact means for each block with which the actuating means on the vehicle coacts to effect an interruption of the normal vehicle circuit; a local current supply; a normal connection between the local current supply and the said contact means; a switch in said connection; means for operating the switch to interrupt said normal connection when slow speed of the vehicle is required and means controlled by the operation of the switch, interposed between the said contact means and track rail to send current from the said local current supply through the controlling device on the vehicle when the latter is traveling at the required low speed.

9. A safety controlling device for railways wherein the vehicle is provided with a controlling device, an actuating device and a normal vehicle circuit controlled by the actuating device and including the said controlling device, in combination with the track rails formed into blocks; a contact means for each block with which the actuating means on the vehicle coacts to effect an interruption of the normal vehicle circuit; a local current supply; a normal connection between the local current supply and the said contact means; a switch in said connection; means for operating the switch to interrupt said normal connection when slow speed of the vehicle is required; an electrically-actuated device brought into interposed relation between the said contact means and track rail upon the operation of the said switch whereby said electrically-actuated device may be operated by current from the vehicle and means operated by said electrically-actuated device to permit current from the said local current supply to pass through the controlling device on the

vehicle when the latter is traveling at the required low speed.

10. A safety controlling device for railways wherein the vehicle is provided with a controlling device, an actuating device and a normal vehicle circuit controlled by the actuating device and including the said controlling device, in combination with the track rails formed into blocks; a contact means for each block with which the actuating means on the vehicle coacts to effect an interruption of the normal vehicle circuit; a local current supply; a normal connection between the local current supply and the said contact means; a switch in said connection; means for operating the switch to interrupt said normal connection when slow speed of the vehicle is required, and timing means brought into interposed relation between said contact means and track rail upon the operation of the switch whereby said timing means may be operated by current from the vehicle to form a circuit from said timing means may be operated by controlling device on the vehicle when the latter is traveling at the required low speed.

11. A safety controlling device for railways wherein the vehicle is provided with a controlling device, an actuating device and a normal circuit controlled by the actuating device and including the said controlling device, in combination with the track rails and contact means at intervals along the track with which latter the actuating means on the vehicle co-acts; timing means; means for throwing the timing means in the circuit on the vehicle when the actuating device on the vehicle co-acts with the contact means along the track to set the timing means in motion and means actuated by the timing means after a predetermined interval for providing a substitute circuit through the controlling device on the vehicle if the actuating device on the vehicle is still in engagement with a contact means when the timing means has completed its operation.

In testimony whereof I affix my signature in presence of two witnesses.

FRANK T. JONES.
